Ottó Klein Inventor
By his Attorney
Mark V. Ordway

UNITED STATES PATENT OFFICE.

OTTO KLEIN, OF PATERSON, NEW JERSEY.

TARGET.

1,342,022.

Specification of Letters Patent.

Patented June 1, 1920.

Application filed September 30, 1919. Serial No. 327,412.

To all whom it may concern:

Be it known that I, OTTO KLEIN, a citizen of the United States of America, residing at Paterson, in the county of Passaic and State 5 of New Jersey, have invented certain new and useful Improvements in Targets, of which the following is a specification.

The present invention has reference to targets of the kind described and shown in 10 my United States Patents No. 1,072,621 and No. 1,100,246. The chief object of my invention is to provide a target which, irrespective of the distance it is located, will permit the user to determine the distance 15 and location from the bull's eye of the mark made on the target.

Another object of my invention is to provide a construction which will be simple and durable.

20 With these and other objects in mind, my invention consists of the construction, combination and arrangement of parts herein-after more fully described and set forth with the appended claims.

25 In the accompanying drawing in which similar reference characters denote corresponding parts Figure 1 is a front elevation of the new target; Fig. 2 is a vertical cross section on line 2—2 of Fig. 1; Fig. 3 is a front elevation of a mark recording mechanism; Fig. 4 is a vertical cross section on line 4—4 of Fig. 3; Fig. 5 is a perspective, more or less diagrammatic view of the target and mark recording mechanism 30 showing their operative connection; and Fig. 6 is an enlarged perspective view of the record controlling mechanism.

Referring specifically to the drawing, the target comprises a box or casing *a* of substantially rectangular shape in which the target is arranged and which has an open front *a*¹ adapted to be closed by a cover *b* having a circular hole *b*¹ conforming in size with that of the target proper *T* so that the latter is fully exposed to the view of the user. The target proper consists of a circular disk composed of a plurality of concentric sections 6, 7, 8, 9, and 10 of which section 10 forms the central part of the target disk and serves as the bull's eye. In the drawing the target is shown composed of five sections, the number of sections, however, can be varied according to convenience. Extending transversely inside the box and 45 near the rear wall thereof in a spindle *c* from which are tiltably suspended a plu-

rality of rigid members adapted to carry the different sections composing the target disk *T*. These members extend downwardly across the back of the target and each member has attached to it or is formed integrally with an arm fixed to a section of the target. Each section is adapted to be suspended by a plurality of members all having their arms fixed to different quadrants 60 thereof.

In the present embodiment of my invention each section is carried by four arms, one for every quadrant. Thus for instance the outermost section 6 is carried by arms 70 *e*¹, *e*², *e*³, *e*⁴ formed on or fixed to the corresponding bars or members *d*¹, *d*², *d*³, and *d*⁴. The points of attachment of these arms to the sections 6 are each located in a different quadrant of the annular section 6. The 75 object of this arrangement will be explained hereinafter.

For the attachment of the arms *d*¹, *d*² . . . to the sections 6, 7, 8 . . . I provide each section with a number of eyes *f* or the like 80 which project from the rear face thereof, and to which the arms are riveted or otherwise fixed. For the bull's eye section 10 only one member *d*¹⁰ is used having an arm *e*¹⁰ fixed to the eye *f* which projects centrally from the rear face of the section 10.

Fixed to the rear wall of the casing and near the bottom thereof is a rectangular frame *h* having in each of its longitudinal edges a plurality of parallel recesses or 90 grooves *i* corresponding in number with that of the members *d*¹, *d*² . . . , the two sets of recesses register with one another and with the members *d*¹, *d*² . . . Slidably guided in these grooves are bars *j* of varying lengths, there being as many bars as members *d*¹, *d*² . . . Each bar is formed with a stop *j*¹ at its lower end and with a further stop *j*² at an intermediate point of its length, the lower stop being adapted to 95 limit the movement of the bar in its upward direction by striking against the lower face of the bottom of the frame *h*, while the intermediate stop *j*² is adapted to limit the movement of the bar in the downward direction on striking the upper face of the top of the frame *h*. By these means the bars *j* are capable of a restricted vertical movement, each of varying stroke. The portion of the bar *j* projecting upwardly 100 beyond the intermediate stop *j*² is provided with a longitudinal groove *j*³ which may be

formed by bending the upper portion of the bar j upon itself. These loop-shaped or grooved upper ends of the members j are all of equal length and normally the same 5 will extend evenly with one another while their lower ends will project downwardly from the frame at different levels.

Fulcrumed in the groove j^3 of each member j to swing vertically is a hook-shaped 10 member or catch k . This member or catch is so shaped and admeasured that normally its back will project outwardly from the groove or loop j^3 toward the rear of the target disk and with its free end will slightly 15 project from or be flush with the rear edge of the frame h . While the top of the hook by abutting against the top wall of the groove j^3 will hold the catch against swinging forwardly from the normal position, the 20 hook is free to swing rearwardly *i.e.* toward the back of the box, but is so balanced that it will have the tendency to remain in or return into said normal position when thrust rearwardly. The bars d^1 , d^2 each carry 25 hammers g or the like projecting rearwardly from the lower ends, these hammers being arranged so as to register with the lower parts of the backs of the catches k and when the latter are in normal position to be but a 30 very short distance removed therefrom. The free space between the hammers and catches must be sufficient to prevent accidental contact between them.

Extending above the frame h is a second 35 rectangular frame l which is capable of vertical movement. This frame is substantially of the same length as the lower frame h and by suitable means is guided in vertical direction parallel to itself. In the present embodiment of my invention I provide posts or 40 rods m projecting upwardly from the top of the frame h and suitably fixed thereto, there being one post or rod near each end of the frame h . The frame l is provided 45 with perforated members n at each end slidably engaging the said posts or rods m . In its vertical movement the frame l is adapted to pass through the path described by the catches when tilting rearwardly, so that 50 when one of the catches happens to have been thrust rearwardly by the corresponding hammer it will be brought into engagement with said frame. In consequence thereof the continued movement of the frame l will 55 lift upwardly the bar j carrying the particular catch. Inasmuch as the bars j have varying strokes, as was heretofore described, the extent of the upward movement of the frame l will vary, according to the stroke of the 60 bar of the particular catch by which it is caught. This variable movement is indicated on a separate register which may be arranged near the shooter, so that without moving away from his position or without 65 any assistance he may be able to determine

the approximate location of the mark made by him on the target.

The register is constructed as follows:

In a plate or board o is rotatably mounted a pulley p which on its face carries a finger q or indicator q projecting radially from the circumference thereof. Fixed to the pulley and adapted to wind around the same is a wire or cord r which with its other end is connected to the vertically movable frame l 75 and which is suitably guided over sheaves s . By revolving the pulley p by means of a knob p^1 or the like the frame l will be moved upwardly and if a catch k happens to be in engagement with it the movement will be 80 limited according to the stroke of the bar of that particular catch. This limitation will be indicated by the finger q on a dial u . The markings on the dial are arranged according to the different strokes of the 85 frame l . In the present embodiment of my invention there are five sections composing the target and four bars j for each annular section and one for the bull's eye section 10. The dial accordingly has seventeen markings 90 u^1 for the different strokes of the frame l , one extra marking for the zero position. At this zero marking a stop v is provided which coöperates with the finger q . The division points on the dial are marked with figures 95 identifying the sections of the target and the quadrants thereof. Thus 10, 9 with a dot at the upper right, 9 with a dot at the lower left. Similarly with 8, 7, 6. The dots denote the quadrants. The divisions are 100 made to correspond with the different strokes of the frame l . Thus the circumference of the pulley p corresponds with the maximum stroke of the frame when not engaged by any of the catches k . The arc from zero 105 to division 10 corresponds with the smallest stroke of the frame which may be selected for the bull's eye section, etc.

The mode of operation of my target is as follows:

When one of the sections of the target is struck the impulse received by the same will be transmitted through the quadrant at which it was struck to the hammer g of the bar connected to it, and in consequence thereof the hammer will be thrust against the corresponding catch tilting the latter rearwardly into engagement with the frame. The shooter will then turn the pulley p , thereby lifting the frame l . The stroke of 110 the movement of the frame l will be determined by the particular section and quadrant of the section struck. The marking on the dial u at which the pointer q turning with the pulley will stop at the end of the 115 upward stroke of the frame l will tell the shooter the approximate location of the mark made by him on the target.

The return of the frame l into normal 120 position and of the pointer q into zero will 125 130

be effected by the weight of the frame *l* and the bars *j* suspended therefrom.

Since various modifications may be made in the construction without departing from 5 the principle of my invention I do not wish to restrict myself to the details shown and described, except in so far as they are limited by the appended claims.

What I claim is:

10 1. In a target, the combination with a target disk composed of individual sections, of a movable record controlling means, a plurality of movable members, capable of separately engaging said means, means for 15 limiting the strokes of said members and means on said sections capable when a section of the target is struck of effecting such engagement between the corresponding movable member and said movable means so 20 that when the latter is moved its stroke will be limited by said members.

2. In a target, the combination with a target disk composed of individual concentric sections, of a movable record controlling 25 frame, a plurality of movable members capable of separately engaging said means, means for limiting the strokes of said members, and means on said concentric sections capable when a section of the target is 30 struck of effecting such engagement between the corresponding movable member and said frame, so that when the latter is moved its movement will be limited by the particular movable member.

35 3. In a target, the combination with a target disk composed of individual sections, of a vertically movable record controlling frame, a plurality of vertically movable members capable of separately engaging 40 said frame, means for limiting the strokes of said members and means on said sections capable when a section of the target is struck of effecting such engagement between a corresponding movable member and said 45 frame, so that when the latter is moved, its stroke will be limited by said movable member.

4. In a target, the combination with a target disk composed of individual sections, 50 of a vertically movable frame, a plurality of vertically movable members capable of separately engaging said frame, means for limiting the strokes of said movable members, means on said sections capable when a 55 section of the target is struck of effecting such engagement between a corresponding movable member and said frame, so that when the latter is moved vertically upward, such movement will be limited by said member and a mark recording device operatively connected to said movable frame.

5. In a target, the combination with a target disk composed of individual concentric sections, of a vertically movable record controlling frame, a plurality of vertically mov-

able members capable of separately engaging said frame, means for limiting the stroke of said members, and means on each quadrant of said concentric sections capable when a quadrant of said target sections is struck of effecting such engagement between a corresponding member and said frame, so that when the latter is moved upward, its stroke will be limited by said member.

6. In a target, the combination with a target disk composed of individual sections, of a vertically movable record controlling frame, independently movable bars, a grooved guide for said bars, means on said bars limiting the movement thereof in said guides, a catch on each of said bars and means on said individual sections adapted when the target is struck to bring the corresponding catch into engagement with said movable frame and to thereby limit the stroke of said frame.

7. In a target, the combination with a target disk composed of individual concentric sections, of movable arms from which said sections are suspended, a movable frame 90 at the rear of said arms, a plurality of movable members capable of separately engaging said frame, means for limiting the stroke of said movable members, means on said arms adapted when a section of the target is struck to effect such engagement between a corresponding member and said frame and to limit the movement of the latter to a predetermined stroke and a mark recording device operatively connected to 95 said movable frame.

8. In a target, the combination with a target disk composed of individual concentric sections, of movable arms from which said sections are suspended, there being an 100 arm for each quadrant of the annular target sections, a movable frame at the rear of said arms, a plurality of movable members capable of separately engaging said movable frame, means for limiting the stroke of said 105 movable members, means on each arm for effecting such engagement between a corresponding member and said frame when a section of the target is struck and a mark recording device operatively connected to 110 said movable frame.

9. In a target, a target disk composed of individual sections, freely suspended arms carrying the sections of said target disk, a movable means at the rear of said arms, a 115 series of independently movable members, means for limiting the stroke of said movable members, means on each of said members capable of independently engaging said movable means and adapted to be normally 120 out of engagement therewith but to engage the same when moved by the struck target section and a mark recording device operatively connected to said movable means.

10. In a target, a target disk composed of 130

- individual concentric sections, a plurality of swinging members for said sections attached to different points thereof, movable means, means for limiting the strokes of said movable means, means actuated by said swinging members to cause the engagement of said two first-named means and a mark recording device operatively connected to said first-named means.
- 10 11. In a target, a target disk composed of individual sections, a plurality of swinging members for said sections attached to different points thereof, a plurality of members capable of vertical movement at different strokes, a single movable member capable of coöperation with any one of said vertically movable members, independently acting catches on said vertically movable members capable of engaging said single
- 15 20 movable member and operated from the said swinging members and a mark recording device operatively connected to said single

member and controlled by the variable movements thereof.

12. In a target, a target disk composed of 25 individual independently swinging sections, a mark recording device comprising a rotary member having a pointer and a dial around said rotary member, means capable of variable movements and operatively connected 30 to said rotary member, and means whereby when a section is struck the stroke of said means will be fixed permitting the rotary member to be turned around its axis an arc corresponding to said stroke, and which will 35 be indicated on the dial by said pointer designating the location of the mark on the target.

In testimony whereof I affix my signature in presence of two witnesses.

OTTO KLEIN.
